UNITED STATES PATENT OFFICE.

OTTO LAUBER AND FRIEDRICH STOCK, OF ESSEN-ON-THE-RUHR, GERMANY,
ASSIGNORS TO FRIED. KRUPP, OF ESSEN-ON-THE-RUHR, GERMANY.

ORDNANCE.

SPECIFICATION forming part of Letters Patent No. 718,004, dated January 6, 1903.

Application filed February 24, 1902. Serial No. 95,411. (No model.)

To all whom it may concern:

Be it known that we, OTTO LAUBER and FRIEDRICH STOCK, residing at Essen-on-the-Ruhr, Germany, have invented certain new and useful Improvements in Ordnance, of which the following is a specification.

The present invention relates to ordnance in which the gun-barrel alone recoils; and its object is to provide means for "braking" the recoil and bringing the barrel forward again and whereby the employment of the hydraulic brake is rendered unnecessary. According to the present invention this end is attained by connecting the barrel by means of staff-shaped lamellæ which pass through an elastic lamellæ pressure-bearing to the movable abutment for the returning-spring.

A form of construction of the invention is illustrated in the accompanying drawings.

Figure 1 shows, partly in side elevation and partly in longitudinal section, an apparatus according to this invention in connection with those parts of a gun with which the same coacts, the said parts being shown in the firing position. Fig. 2 is a section on the line 2 2 of Fig. 1 looking from the left. Fig. 3 is a side elevation of that part of the device next the breech end of the gun and in the position which the parts assume directly after the commencement of the recoil. Fig. 4 is a side elevation of the plate-pressure bearing in the position of rest and on a larger scale. Fig. 5 is the corresponding top plan. Fig. 6 is a section on the line 6 6 of Fig. 4 looking from the left. Figs. 7 to 9 show a detail, hereinafter referred to, in side, end, and plan views. Fig. 10 is a view of the movable abutment for the returning-spring. Fig. 11 shows in plan, on a reduced scale, the lamellæ disconnected from the gun.

The gun is carried in the usual way in a cradle A, in the L-shaped trough of which the device for braking the recoil and bringing the barrel forward again is mounted. (See Fig. 1.) The staff-shaped lamellæ B' B² B³, of which the lamellæ B' B² are of variable breadth for a purpose to be hereinafter explained, are rigidly attached to the horn D of the breech-piece, and consequently take part in both the recoil and forward movement of the barrel. The ends of the

lamellæ B' B² B³ next the muzzle of the gun are rigidly attached to a sleeve E, while an internal screw-thread on this sleeve engages a head-screw F, against which lies the abutment G for the returning-spring. This abutment G (see also Fig. 10) consists of two concentric rings, which are connected together by two cross-pieces g, diametrically opposite each other. The inner ring of the abutment G embraces the sleeve E, the outer ring and the cross-pieces g being designed to guide the abutment upon a sleeve K during the recoil and forward return of the gun-barrel. This sleeve K is provided, for the purpose of guiding the abutment, with two longitudinal slots k along the greater part of its length. The returning-spring H is pushed onto the sleeve K and bears at one end against the movable abutment G and at the other end against an annular flange h on the sleeve K. This flange bears against a vertical abutment I, rigidly connected to the cradle and which is provided with a recess for the staff-shaped lamellæ B' B² B³. The elastic lamellated pressure-bearing, Figs. 1, 3, and 4 to 6, through which the staff-shaped lamellæ pass, consists of plate-formed lamellæ C' C² C³ C⁴, two sets of plate-springs P, and abutment-plates N for these springs. The parts of this pressure-bearing are horizontal and are inclosed between two vertical plates M, connected by stay-bolts m, so that they are free to move vertically within these plates M. The lamellæ C' C² C³ C⁴ are so arranged that one staff-shaped lamellæ B', B², or B³ passes between each two. The springs P lie between the outer lamellæ C' C⁴ and the abutment-plates N. Above and below the pressure-bearing is arranged a wedge-shaped plate R. One plate R lies close to the under side of the slide for the barrel and the other on the bottom of the cradle A. These plates R form a casing, which decreases in height in the direction of the recoil and in which the pressure-bearing, with the plates M, between the abutment L and a second vertical abutment S, likewise rigidly connected with the cradle, is free to slide. This abutment S is provided with recesses for this purpose, in which the nuts of the stay-bolts m can enter. Between the abutment-plates N and the wedge-shaped

plates R are arranged balls Q, for which race-ways are provided in the plates R and N. The plates R may be adjusted in the direction of the return movement by means of a screw-spindle s engaging the abutment S and are guided for this purpose in recesses in the plates M. Like the abutment L, the plates M and the abutment S are also provided with slots for the staff-shaped lamellæ B' B² B³. Upon each of the lower stay-bolts is mounted a rotating angle-lever T. (See Figs. 4 to 9.) The lower arm t of this lever lies against the lower abutment-plate M, while the upperarm of the angle-lever has a rotating axle U journaled in it. Upon this axle are mounted, on a level with the two lower staff-shaped lamellæ B' B² and in recesses in the lever T, eccentric or eccentric collars w' w², each prevented from rotating by a nose u on the axle U, Figs. 6 and 9, and carrying rollers W' and W². The upper end of the axle U is shaped into a crank V, to the pin v of which is attached a pull-rod Z. These pull-rods are attached to eyes z in the abutment S and are intended to alternately throw into or out of action the rollers W' W², so that either the rollers W' co-operate with the lamella B' or the rollers W² with the lamella B³, as will be hereinafter more particularly described.

In the position of rest or the firing position the various parts assume the position shown in Figs. 1 and 4 to 6. When the gun-barrel recoils after firing, it carries the staff-shaped lamellæ B' B² B³ with it, so that the returning-spring H is compressed by means of the abutment G.

The elastic lamellæ pressure-bearing takes part in the recoil on account of the friction set up between the lamellæ B' B² B³ and the lamellæ C' C² C³ C⁴ until it strikes the abutment S. (See Fig. 3.) Through this shifting of the pressure-bearing the springs P are forced together by the action of the wedge-shaped plates R, so that the brake-pressure suddenly increases. Simultaneously the cranks V are turned toward the muzzle of the gun by the rods Z. This rotation is followed by the axles U and the eccentric collars w' w², so that the rollers W' move out of the path of the varying surface of the lamella B' or are thrown out of action, and the rollers W² are turned so as to lie close to the varying surface of the lamella B³ or thrown into action. As the recoil proceeds the brake-pressure increases, the rollers w² co-operating with the gradually-increasing width of the lamella B³. When the barrel has reached the utmost limits of the recoil, it is again brought back to the firing position by the returning-spring. At the commencement of the return the lamellæ pressure-bearing is carried forward by the lamellæ B' B² B³ back to its position of rest, so that the pressure-bearing expands and the brake-pressure suddenly diminishes. Simultaneously the cranks V are again returned to the position shown in Figs. 4 to 6. The rollers W² are consequently dis-

engaged from the lamella B³, while the rollers W' are again brought into contact with the lamella B', which latter, as the returning movement proceeds, regulates the brake-pressure according to its varying width.

If no stress be laid upon a regulation of the return differing from the regulation of the recoil, the brake-pressure might obviously be regulated by dispensing with the one roller, (W' or W²), as well as the device for advancing or withdrawing the rollers and using only a single lamella of varying breadth. Likewise one or more of the staff-shaped lamellæ might be made of constant breadth and varying thickness. In such case the staff-shaped lamellæ might be fixed and the elastic lamellæ pressure-bearing so connected to the gun-barrel (the lever T being omitted) as to take its part in the whole of the recoil and stopper thereof.

What we claim as new is—

1. In a brake for guns, the combination of a cradle, a barrel sliding on said cradle, and a return-spring having a fixed abutment attached to the cradle and a movable abutment sliding in the cradle, with a series of staff-shaped lamellæ connecting said movable abutment to the barrel and a lamellated pressure-bearing guiding said staff-shaped lamellæ, substantially as and for the purpose specified.

2. The combination with a cradle, a barrel sliding on the cradle, and recuperating means, of a friction-brake connecting the barrel with the recuperating means.

3. In a brake, the combination with a cradle, a barrel sliding on the cradle, and a return-spring, of a friction-brake arranged within the return-spring and connecting the barrel with the same.

4. In a brake, the combination with a cradle, a barrel sliding on the cradle, and a return-spring, of lamellæ connecting the gun to the return-spring, and means compressing the lamellæ upon the recoil movement of the gun.

5. In a brake for recoil-guns, the combination with a cradle, a barrel sliding on said cradle, a sleeve connected to the cradle and a return-spring surrounding the sleeve, of a series of lamellæ arranged within the sleeve and connected to the barrel and to the sleeve, a series of lamellæ carried by the cradle and arranged in frictional relation with the lamellæ carried by the barrel, and means for pressing both series of lamellæ together.

6. A brake for recoil-guns, comprising recuperating means, lamellæ arranged in frictional relation and connected respectively with the gun and its mount, and means for pressing said lamellæ together, applied by the recoil movement, and also by the return movement of the gun.

7. The combination with a gun, and the recuperating means, of the lamellæ, and means for compressing the lamellæ together on the recoil and also on the return movement of the gun.

8. In a brake for recoil-guns, the combina-

tion with a cradle, a barrel sliding on the cradle, a sleeve connected to the cradle, and a return-spring surrounding the sleeve, of lamellæ arranged within the sleeve and connected to the barrel and to the spring, an elastic friction device through which the lamellæ work having a limited play thereon, and wedging-plates one of which is fixed and the other of which partakes of the limited play of the friction device.

9. In a brake for recoil-guns, the combination of a lamella, and the elastic friction device through which it works, one of which parts is connected with the gun and the other with the gun-mount, but having a limited play thereon, and wedging-plates, one of which is fixed, and the other of which partakes of the limited play of the friction device, compressing the friction device on the lamella as recoil takes place, said wedging-plates having interposed balls.

10. A brake for recoil-guns, comprising a lamella, and an elastic friction device through which the lamella works, one connected with the gun and the other with the gun-mount, wedging-plates compressing the friction device when recoil takes place, and a lever carried with the friction device, impinging and receiving movement from the lamella and also compressing the friction device.

11. A brake for recoil-guns, comprising the fixed and moving lamellæ arranged in frictional relation, one of which has a varying surface, means for forcing the lamellæ together to increase the friction between them, operated by the varying surface of the lamella.

12. A brake for recoil-guns, comprising alternated fixed and moving lamellæ, a lever forcing said lamellæ together into frictional relation, and engagement between the lever and the moving lamellæ, moving the lever upon its fulcrum as the gun moves.

13. A brake for recoil-guns, comprising alternated fixed and moving lamellæ, an angle-lever forcing the lamellæ together to increase their frictional relation, and a bearing between a moving lamella and the angle-lever; said moving lamella having a varying surface constructed to move said angle-lever.

14. A brake for recoil-guns, comprising fixed and moving lamellæ in frictional relation one of which is provided with a varying surface, a lever forcing the lamellæ together to increase their friction, and an eccentric interposed between the lever and a moving lamella, causing the former to be moved by the latter.

15. A brake for recoil-guns, comprising fixed lamellæ, moving lamellæ, one of which has a varying surface, and in frictional relation to the fixed lamellæ, and an angle-lever forcing the lamellæ together to increase their frictional relation, having an eccentric bearing against the varying surface of the moving lamella, and receiving therefrom movement which rocks the angle-lever upon its fulcrum.

16. A brake for recoil-guns, comprising

fixed lamellæ, moving lamellæ, one of which has a varying surface, and in frictional relation to the fixed lamellæ, and an angle-lever 70 forcing the lamellæ together to increase their frictional relation, having an eccentric bearing against the varying surface of the moving lamella, and receiving therefrom movement which rocks the angle-lever upon its fulcrum, 75 and means turning said eccentric about its axis for moving it into and out of contact with said varying surface.

17. A brake for recoil-guns, comprising fixed lamellæ, moving lamellæ, one of which 80 has a varying surface, and in frictional relation to the fixed lamellæ, and an angle-lever forcing the lamellæ together to increase their frictional relation, having an eccentric bearing against the varying surface of the moving 85 lamella, and receiving therefrom movement which rocks the angle-lever upon its fulcrum, and means controlled by the movement of the gun, turning said eccentric about its axis and moving it into and out of contact with the 90 varying surface of the moving lamella.

18. A brake for recoil-guns, comprising fixed lamellæ, moving lamellæ, having two varying surfaces, and in frictional relation to the fixed lamellæ, an angle-lever forcing the 95 lamellæ together to increase their frictional relation, when rocked upon its fulcrum, two eccentrics upon said angle-lever arranged to contact with the varying surface of the moving lamellæ, and connections moving one of 100 said eccentrics into impingement with a varying face of a moving lamella during recoil and the other eccentric into impingement with a varying face of a moving lamella during return movement of the gun.

19. A brake for recoil-guns, comprising fixed lamellæ, moving lamellæ, having varying surfaces, and in frictional relation to the fixed lamellæ, an angle-lever forcing the lamellæ together to increase their frictional relation, when rocked upon its fulcrum, two eccentrics upon said angle-lever arranged to contact with varying surfaces of the moving lamellæ when turned upon their axes, and a crank-shaft upon which said eccentrics are 115 mounted, moving one of said eccentrics into impingement with the varying face of a moving lamella during recoil and the other eccentric into impingement with the varying face of a lamella during return movement. 120

20. In a check for recoil-guns, the combination of moving lamellæ, having varying surfaces, an elastic friction device through which the moving lamellæ work, having a limited play, angle-levers partaking of the limited 125 play of the friction device, compressing said friction device upon the moving lamellæ when the angle-levers are rocked upon their bearings, a crank-shaft on each of said angle-levers, eccentrics on said crank-shaft and turning therewith into and out of bearing relation to the varying faces of the moving lamellæ, and connections between said crank-shaft and fixed points whereby they are 130

turned by the limited play of the friction device.

21. In a recoil-gan, a device for braking the recoil, and returning the gun, comprising a movable abutment connected with the gun, a return-spring opposing the movement of said abutment, the series of staff-shaped lamellæ, and the elastic lamellated pressure-bearing, passing the one through the other, and connected respectively with the movable abutment and with a fixed part, a casing R, decreasing in height in the direction of the recoil in which the elastic lamellated pressure-bearing has a limited movement, so that when

carried forward and backward by the staff-shaped lamellæ it is compressed at the commencement of the recoil, but expands on the commencement of the return movement, and accordingly causes the brake-pressure to suddenly increase or decrease.

In testimony whereof we have hereunto set our hands in the presence of two subscribing witnesses.

OTTO LAUBER.

FRIEDRICH STOCK.
